CHECK ROW CORN PLANTER.

No. 293,672.

Patented Feb. 19, 1884.

UNITED STATES PATENT OFFICE.

EARL HOUSTIN REYNOLDS, OF PROPHETSTOWN, ILLINOIS.

CHECK-ROW CORN-PLANTER.

SPECIFICATION forming part of Letters Patent No. 293,672, dated February 19, 1884.

Application filed August 28, 1883. (No model.)

To all whom it may concern:

Be it known that I, EARL H. REYNOLDS, a citizen of the United States, residing at Prophetstown, in the county of Whiteside and State of Illinois, have invented a new and useful Check-Row Corn-Planter, of which the following is a specification, reference being had to the accompanying drawings.

This invention relates to certain improvements in check-row corn-planters; and it has for its object to produce a device which shall possess superior advantages in point of convenience and general efficiency.

To this end it consists in certain improvements in the construction of the same, which will be hereinafter fully described, and particularly pointed out in the claims.

In the drawings hereto annexed, Figure 1 is a perspective view, illustrating my invention in connection with the tappet-wire. Fig. 2 is a transverse vertical sectional view of the same. Fig. 3 is a plan view. Fig. 4 is a vertical sectional view on the line $x-x$ in Fig. 3. Fig. 5 is a detail view, in perspective, of the oscillating guide-plate; and Fig. 6 is a plan view illustrating a modification of my invention.

The same letters refer to the same parts in all the figures.

In the drawings, A A designate the seed-boxes of an ordinary planter to which my invention is applied, and B is the seed-slide.

C C are brackets provided with slots D, to receive the screws or bolts E, by means of which they are secured upon the inner sides of the seed-boxes, as shown. The said brackets carry the cross-bar F, which supports the mechanism of my improved check-rower, which is as follows:

G G are frames or brackets projecting from the ends of the cross-bar F. At the outer corners of said brackets are mounted horizontal pulleys H H, and at the inner corners of said brackets are mounted similar horizontal pulleys I I. The axles or spindles J of the pulleys H, at each end of the machine, are connected by longitudinal guards K, and a transverse guard, L, parallel to the cross-bar F, connects the spindles of the pulleys I, as shown in Figs. 1 and 3 of the drawings.

M is the guide-disk, (see Fig. 5,) which con-

sists of a casting comprising a pair of horizontal parallel cruciform plates, the front and rear arms of which are integrally connected by the loops or bows N N. The upper and lower plates, O and P, are provided, respectively, with upward and downward projecting spindles Q and R, which are journaled, respectively, in the guard L and in the cross-bar F, as shown in Figs. 2 and 4 of the drawings. The side arms, S, of the cruciform plates are connected with the front and rear arms, T, by means of inclined braces U, forming tracks, upon which the tappets of the check-rope may slide, as will be hereinafter more fully described. Metallic braces or stiffeners V are also provided, that connect the ends of the arms S with the loops or bows N, as shown fully in Figs. 1 and 5 of the drawings. The upper spindle, Q, of the guide-disk is provided with a crank, W, which is connected by a pitman, X, with a crank, Y, projecting upwardly from a rock-shaft, Z, journaled in brackets A², longitudinally under the cross-bar F. The rear end of the rock-shaft Z has a crank, B², working in a slotted bracket, C², projecting upwardly from the seed-slide, which is thereby operated, as indicated in Figs. 1 and 2 of the drawings.

C³ designates the tappet-wire, which is equipped in the usual manner with buttons or tappets D², and which is stretched upon the field in the well-known manner, it being attached at its ends to suitable anchors, E², one of which is shown in Fig. 3 of the drawings.

The operation of this invention will be readily understood from the foregoing description, taken in connection with the drawings hereto annexed. The tappet-wire passes over the front pulley, H, at one end of the machine, between the guide-pulleys I I, between the plates forming the guide-disk, between guide-pulleys I I, and over the pulley H, at the other end of the machine, as seen in Fig. 3. As the machine progresses over the field, one of the tappets, striking one of the inclined tracks U, will move along the said track until the adjoining arm T is encountered, when the guide-disk will be oscillated or swung upon its bearings until the tappet may pass through the loop or bow N. It will then pass between the guide-pulleys I I, and will thus cause the wire

to pass between the plates composing the 5 guide-disk, thus directing the next tappet against the inclined track U on the other side of arm T, and causing a repetition of the operation, which will continue until the end of the field is reached. The device, it will be seen, will work equally well from either side.

In Fig. 6 of the drawings I have illustrated 10 a modification of my invention, by which I avoid guiding the tappet-wire across the machine, as described in the foregoing. The cross-bar F is in this case provided with brackets F², one at each end, forming bearings for the upper spindles of the guide-disks G², the 15 lower spindles of which are journaled in cross-bar F. The said guide-disks in this case consist of bars H², the inner ends of which are connected by loops or bows I², and the outer ends of which are forked. Said bars have for- 20 wardly-projecting arms J², the sides of which are connected with said bars by inclined braces K². Horizontal guide-pulleys L² are mounted upon brackets M², projecting diagonally forward from the cross-bar F. The upper spindles 25 of the guide-disks, at each end of the machine, are provided with cranks N², connected by a rod, O², which is pivotally connected with the crank Y, projecting upwardly from the rock- shaft Z. The operation is obvious.

30 I claim as my invention and desire to secure by Letters Patent of the United States—

1. In a check-row corn-planter, the combination, with the seed-boxes, connected seed-

slide, and brackets, of the cross-bar F, the 35 end frames, G G, provided with horizontal pulleys H and I, the parallel guards K and L, connected to the axles of the pulleys, and the guide-disk M, substantially as and for the purpose set forth.

2. In a check-row planter, the guide-disk 40 M, consisting of the horizontal cruciform plates O P, with the oppositely-arranged loops N N, the braces U and V, and the upper and lower spindles, Q R, as described.

3. In a check-row planter, the combination, 45 with the guide-disk M, constructed substantially as described, of the crank W, attached to the upper end of the spindle Q thereof, pitman X, crank Y, rock-shaft Z, with crank B², and seed-slide C, with bracket C², substantially 50 as and for the purpose set forth.

4. As an attachment to a planter, the cross-bar F, with the end frames, G G, provided with pulleys H and I, and guard-plates K K, the cruciform guide-disk M, connected to the cross-bar F, and a transverse guard-plate, L, the crank W, pitman X, crank Y, rock-shaft Z, 55 with crank B, and slotted bracket C², substantially as described.

In testimony that I claim the foregoing as 60 my own I have hereto affixed my signature in presence of witnesses.

EARL HOUSTIN REYNOLDS.
